ADOLPH R. HOEFT, OF EVANSTON, ILLINOIS, ASSIGNOR TO HOEFT & COMPANY, INC., OF CHICAGO, ILLINOIS, A CORPORATION OF ILLINOIS

BURNER CONTROL MECHANISM

Application filed October 18, 1930. Serial No. 489,520.

This invention relates to improvements in burner control mechanisms and it consists of the matters hereinafter described and more particularly pointed out in the appended claims.

The primary object of the invention is to provide a thermostatically actuated control mechanism for a burner using liquid fuel and wherein the gravity feed of such fuel from a source of supply is adjusted by changing the relative positions and attending head pressures between said source of supply and the burner.

Another object of the invention is to provide a control mechanism of this kind wherein the burner is movable up or down by a manually operated member to provide an initial adjustment and is thereafter automatically movable with respect to said member by means effected by the temperatures produced by said burner whereby the action of the burner is controlled in a more efficient manner.

These objects of the invention as well as others together with the many advantages thereof will more fully appear as I proceed with my specification.

In the drawings:—

Fig. 1 is a top plan view of a liquid fuel burner embodying my improved control mechanism.

Fig. 2 is a view in side elevation of the same, with parts shown in longitudinal vertical section to more fully illustrate the invention.

Fig. 3 is a perspective view on an enlarged scale of a part of a certain compound lever embodied in my invention and which will be more fully referred to later.

Fig. 4 is a longitudinal vertical sectional view on an enlarged scale through one end of a burner embodying my invention, the plane of the section being indicated by the line 4—4 of Fig. 1.

Fig. 5 is a transverse vertical sectional view through the same as taken on the line 5—5 of Fig. 4.

Fig. 6 is a horizontal detail sectional view as taken on the line 6—6 of Fig. 4.

In general the burner in which my invention

is embodied is one especially adapted for use in brooders and the like, but of course, the same may also be embodied in burners for other purposes, where the peculiar characteristics of the invention make it of advantage to do so. Such a burner comprises a somewhat elongated casing with a chamber at each end and in one chamber is a vertically movable burner and in the other chamber is a liquid fuel reservoir connected to the burner by a relatively long tube. The burner is vertically movable by means of a manually operable, compound lever including a main and an auxiliary lever member whereby said burner may be positioned to determine the desired initial head pressure for the fuel fed thereto. In connection with said lever is provided a thermostatic device which operates through the auxiliary lever member to vertically move the burner, independent of the main lever member to change the head pressure of the fuel in accordance with temperature conditions adjacent said burner.

Referring now in detail to that embodiment of the invention illustrated in the accompanying drawings:— 1 indicates as a whole an open bottom and somewhat horizontally, elongated, sheet metal casing comprising upright, tubular, chamber providing means 2 and 3 respectively at the ends thereof, which members are connected together by a conduit 4. In the tubular member 2 is provided a spider 5 having an axially depending tubular stem 6 in which a post 7 supporting a burner 8 at its top end has sliding guided bearing. In said tubular member 2 above the spider are formed annular rows of openings 9 supplying the air necessary to support combustion and in the tubular stem 6 of said spider, are longitudinally extending slots 10 through which a transverse pin 11 carried by the burner post 7 extends.

In the top end of the upright tubular member 3 is located a liquid fuel reservoir 12 which is connected to the burner by a relatively long feed tube 13, the major portion of this tube being disposed in the conduit 4. By reason of its substantial length, said tube flexes to accommodate for any relative vertical movement between the burner 8 and reservoir 12.

12. In this instance, it is pointed out that said reservoir is so formed as to receive and hold an inverted supply container indicated in dotted lines as at 12^a in Fig. 2, whereby a 5 constant level is maintained in the reservoir.

14 indicates as a whole a main lever member in the form of an edgewise disposed strap, disposed in the longitudinal median plane of the casing and having one end extending 10 through a vertically arranged slotted guide and gauge strip 15 in that part of the member 3 opposite the conduit 4. This part of the lever member is provided with a tooth 16 to so engage the gauge and guide strip 15 as to stay where located.

The other end of said lever member is bent laterally as at 17 at a point spaced from its extremity 18 and has there secured to it a similarly bent strip 19 having an extremity 20, thus providing a yoke 21 at this end of 20 said lever member. A pin 22 extends laterally through the yoke 21 and the side walls of the conduit 4 at this point to provide a pivotal connection between said lever and conduit.

Associated with this last mentioned end of the main lever member and coacting therewith to provide the compound lever before mentioned, is a secondary or auxiliary lever member 23, pivoted at a point midway between its ends as at 24 to and between the lever member and strip extremities 18 and 20 respectively. One end of said secondary lever member is formed to provide a fork 25 that embraces opposite sides of the guide tube 6 of the spider 5 and has longitudinal slots 26 therein to receive the ends of the pin 11 in the burner post 7.

The other end of said secondary lever member is twisted to pass under and engage the pivot pin for the lever yoke 19 as best shown in Figs. 3 and 4 and terminates in a finger 27 disposed in a plane above that of the yoke 19. It is apparent from the construction above described, that when the main lever member 14 is manually actuated to swing about its pivot 22, the secondary lever member 23 swings as a part thereof. It is also apparent that if a downward pressure is exerted upon the finger 27 of the secondary lever member 23 that an upward movement is imparted to the forked end 25 thereof and due to the construction of said end of the secondary lever member with the burner post 55 as before described, a movement is imparted to said post, independent of the main lever 14. In the relative movement between the two lever members, the pivot 22 limits the upward swing of the finger end of the secondary lever member.

When such a burner as described is embodied in a brooder where an even temperature is desired, such a temperature may be thermostatically controlled by operating 65 upon the finger 27 to raise and lower the burn-

er to change its relative position or horizontal plane with reference to that of the reservoir and this difference in position or plane will produce a corresponding difference in head pressure for the liquid fuel.

On the top wall of the conduit 4 above the finger 27 I provide a bowed yoke 28 secured at its ends to said wall. Depending from the center portion of said yoke is a U-shaped bracket 29 in the bottom of which is located a 70 nut 30, a spring 31 being arranged in said bracket between said nut and the yoke. A screw 32 is threaded through said nut and has a bent top end 32^a above the yoke whereby said screw may be threaded through the nut for adjustment purposes. To the bottom end of this screw is secured a pair of 75 expandable and contractible wafers 33 and the bottom wafer carries an axial stem 34 adapted for engagement with the finger 27.

Assume now that the burner as a whole is located in an enclosure such as a brooder and that there is a fuel container 12^a arranged in an inverted position upon the reservoir 12. Also, assume that the burner 8 is in operation 90 and that the lever member 14 has been adjusted to position the burner in that horizontal plane wherein the head pressure of the liquid fuel provides the approximately correct amount of fuel to the burner.

Assume that the screw 32 has been adjusted for the temperature desired to be maintained in the enclosure or brooder. Should the temperature rise in said enclosure or brooder above the predetermined temperature, then 100 the wafer 33 will expand. As the nut 30 is held down to its seat in the bracket 29 by the spring 31 the expansion of the wafers through the stem 32 will depress the finger 27 and will tilt the secondary or auxiliary lever member 23 about its pivotal connection 24 with the lever member 14 and will lift up the forked ends 25 of said lever member 23. By reason of the pin and slot connection 11 and 26 before mentioned, an upward movement is imparted to the burner post 7 and the burner 8 is raised into a plane above that in which it was set by the manipulation of the main lever member, the position of which main lever member remains unchanged. As 110 the burner is thus elevated, it changes the relative horizontal planes between the burner and reservoir so that a difference in head pressure results and the supply of fuel to the burner is correspondingly diminished.

When the temperature in said enclosure or brooder becomes reduced, the wafers 33 contract and this lifts the stem 34 from the finger 27 and the burner descends by gravity, said finger being stopped in the upward movement of engagement with the pin 22. This reestablishes the original difference in elevations between the burner and source of fuel supply as before and feeds an increased amount of liquid fuel to the burner. In this 130

manner the fluctuations in temperature in the enclosure or brooder automatically takes care of the feed of fuel to the burner.

It is pointed out that when the wafers 33 have actuated the finger 27 to change the position of the burner, they may not immediately cease expanding and should the finger engage the lever member 14 at the rear of the yoke, this would resist further movement of the auxiliary lever as said lever member 14 is locked by its tooth engagement with gauge strip 15. Under such conditions this further expansion will "back up" so to speak and will cause the spring 31 to compress and therefore, nothing can break in the controlling device.

It is apparent that the feed of liquid fuel to the burner is controlled by the temperature within the enclosure or brooder, independent 20 of the initial setting of the burner by manipulation of the lever member 14.

While in describing the invention, I have referred in detail to the form, arrangement and construction of the parts thereof, the same 25 is to be considered merely as illustrative so that I do not wish to be limited thereto except as may be specifically set forth in the appended claims.

I claim as my invention:—

1. A burner control mechanism, embodying therein a burner member, a liquid fuel supply member, one of said members being movable relative to the other to vary the head pressure of said fuel fed to the burner member, manually operable means for moving said one of said members to approximately the desired position including a two-part lever and temperature responsive means operatively engaged with one of said lever parts for automatically moving said one of said members independent of the other part of said lever of said manually operable means.

2. A burner control mechanism, embodying therein a burner member, a liquid fuel supply member, one of said members being movable relative to the other to vary the head pressure of said fuel fed to the burner member, manually operable means for moving said one of said members to approximately the desired position including a two-part lever, temperature responsive means operatively engaged with one of said lever parts for automatically moving said one of said members independent of the other part of said lever of said manually operable means and means for adjusting the action of said temperature responsive means.

3. A burner control mechanism, embodying therein a burner member, a liquid fuel supply member, one of said members being vertically movable with respect to the other to vary the head pressure of the liquid fuel fed to the burner member, a main lever member 65 and a secondary lever member operatively

connected to one of said members for moving the same into approximately the desired position with respect to the other and temperature responsive means operating upon the said secondary lever member for moving said one of said members independent of said main lever member.

4. A burner control mechanism, embodying therein a burner member, a liquid fuel supply member, one of said members being vertically movable with respect to the other to vary the head pressure of the liquid fuel fed to the burner member, a main lever member and a secondary lever member operatively connected to one of said members for moving the same into approximately the desired position with respect to the other, temperature responsive means for operating said secondary lever member for moving said one of said members independent of said main lever member and means for adjusting the action of said temperature responsive means with respect to said secondary lever member.

5. A burner control mechanism, embodying therein a liquid fuel reservoir, a burner connected to said reservoir but movable with respect thereto to vary the head pressure of liquid fuel fed to said burner, manually operable means for moving said burner with respect to the reservoir to approximately the desired position including a two-part lever and temperature responsive means operatively engaged with one of said lever parts for automatically moving the burner independently of the other lever part of said manually operable means.

6. A burner control mechanism, embodying therein a liquid fuel reservoir, a burner connected to said reservoir but movable with respect thereto to vary the head pressure of liquid fuel fed to said burner, a main lever member and a secondary lever member operatively connected to the burner for moving the same into approximately the desired position with respect to the reservoir and temperature responsive means operating upon the secondary lever member for moving said burner independent of said main lever member.

7. A burner control mechanism embodying therein a liquid fuel reservoir, a burner connected to said reservoir but movable with respect thereto to vary the head pressure of liquid fuel to said burner, a pivoted main lever member, a secondary lever member operatively engaged with the burner and pivoted on the main lever member and operable to move the burner into the desired approximate position with respect to the reservoir and temperature responsive means acting upon said secondary lever member to move the burner independent of the main lever member.

8. In combination with a casing having end chambers and a conduit connecting said cham-

bers, a burner vertically movable in one chamber and a reservoir mounted in the other chamber, a tubing connecting said reservoir and burner and extending through the conduit, a compound lever in said conduit and including a main lever member pivoted in the conduit and a second lever member pivoted on the main lever member and operatively engaged with the burner, said main lever member extending through one of said chambers for manipulation to move the burner into approximately the desired position and means operating upon the secondary lever member for moving the burner independent of the main lever member.

9. In combination with a casing, having end chambers and a conduit connecting said chambers, a burner vertically movable in one chamber and a reservoir mounted in the other chamber, a tubing connecting said reservoir and burner and extending through the conduit, a compound lever in said conduit and including a main lever member pivoted in the conduit and a secondary lever member pivoted on the main lever member and operatively engaged with the burner, said main lever member extending through one of said chambers for manipulation to move the burner into approximately the desired position, temperature responsive means supported upon said conduit and having a part extending thereinto, to engage and cause said secondary lever member to move the burner independent of the main lever.

10. In a burner control of the kind described, a compound lever comprising a main lever member pivoted at a point between its ends and a secondary lever member connected at a point between its ends to one end of said main lever member for a swinging movement which is limited by one end of said secondary lever member.

11. In a burner control of the kind described, a compound lever comprising a main lever member formed with a yoke near one end and a secondary lever member pivoted to said end of said main lever member, one end of said secondary lever member having a finger positioned substantially above the yoke and the other end of said secondary lever being formed for connection to a burner supporting member.

12. In combination with a casing having end chambers and a conduit connecting said chambers, a burner vertically movable in one chamber and a reservoir mounted in the other chamber, tubing connecting the reservoir and burner, a lever arranged in said conduit and pivoted at a point between its ends therein, means providing an operative connection between one end of said lever and said burner for raising and lowering the same to adjust it with respect to the reservoir and means formed on the chamber associated with the reservoir for engagement with the other end

of said lever for holding it in the desired adjusted position.

In testimony whereof, I have hereunto set my hand this 15th day of October, 1930.

ADOLPH R. HOEFT.
